Patented Feb. 16, 1965

200,374

SAUNA HEATER

Larry O. Partanen, 4549 Goya Parkway,
Sacramento, Calif.

Filed Aug. 30, 1963, Ser. No. 76,409

Term of patent 14 years

(Cl. D81—20)

FIG. 1

FIG. 2

FIG. 3

FIG. 4

FIG. 1 is a top plan view of a sauna heater, showing my new design;

FIG. 2 is a front elevational view;

FIG. 3 is a side elevational view; and

FIG. 4 is a bottom plan view.

The side not shown is substantially identical to the side illustrated in FIG. 3.

I claim:

The ornamental design for a sauna heater, as shown and described.
